VISE HANDLE HAVING PLURAL CAMS TO
SEQUENTIALLY EFFECT QUICK-POSI-
TIONING AND WORK-CLAMPING MOVE-
MENTS OF SLIDABLE JAW

Alf Nikolaj Johansson, Bleket, Sweden

Application October 28, 1946, Serial No. 706,117
In Sweden October 13, 1945

7 Claims. (Cl. 81—26)

1

The present invention refers to an arrangement in vises and similar apparatus for the securing of work pieces and the like, in which vises a movable clamping jaw is adapted to be pressed against a fixed jaw by means of a cam face on a swingable lever, which is carried by a slide piece adapted, by means of shanks or arms movable relatively to each other, to grip about a guide, said shanks being adapted to be compressed about the guide, in order thus to lock the slide piece by the swinging of the lever from an inoperative position about a bifurcated pivot formed by the end portions of said shanks. The invention has for its object to provide certain improvements in vises of the type referred to, which will appear from the following description in connection with the accompanying drawing, in which:

Fig. 1 is a partly sectional elevation of a vise arranged in accordance with the invention. Fig. 2 shows a section on line II—II in Fig. 1. Fig. 3 is an elevation of the slide piece with its pivot and with a lever arranged thereon. Fig. 4 is a top plan view of the mounted end of the lever. Figs. 5 and 6 show a modified embodiment of the lever and the slide piece viewed from above.

In Fig. 1, 1 designates a fixed jaw, which is connected to an attaching plate 2 to secure the device to a work bench or the like. Rigidly connected with the fixed jaw 1 is a guide bar 3 having a displaceable jaw 4 running thereon. The two jaws 1 and 4 cooperate with each other in the same way as the jaws of an ordinary vise.

Arranged in a guide recess 5 in a projecting portion of the jaw 4 is a slide piece 6 running on the guide 3, the configuration of which also appears from Figs. 2 and 3. The slide piece may be displaced to a certain extent within the guide recess 5, which is limited rearwardly by a screen 7 rigidly connected with the jaw 4. The slide piece has two shanks 6a and 6b forming together a pivot 8 at the top, which is divided into two parts 8a and 8b by the slit 9. By the pivot parts 8a and 8b being pressed against each other, the resilient shank portions 6a and 6b may also be pressed against each other so as to clamp the slide piece fast on the guide bar 3. Pivoted on the pivot is a lever 10 provided with a cam surface 11, which upon turning of the lever is caused to bear on a cooperating surface 12 on the jaw 4.

The two pivot portions 8a and 8b are shaped so as to form together an upwardly tapering cone, the bearing opening 13 of the lever 10 mounted on the pivot being conically shaped in a corre-

sponding manner. The end portion of the pivot is threaded and carries a nut 14, which is secured in its screwed-in position by means of a pin inserted into a transversely extending slot 15. 5 Arranged on the lower side of the nut on both sides of the thread opening are transversely extending projections 16 adapted in the inoperative position of the lever 10 to enter corresponding recesses 17 in the lever. The projections 16 form 10 cam surfaces cooperating with corresponding oblique guide surfaces on the lever. When the lever is turned from its inoperative position shown in the drawing, the cam and guide surfaces 16, 17 extending in the axial direction of the pivot 15 will cause the lever to be displaced downwardly on the pivot portions 8a and 8b, which are then pressed against each other by the cooperating conical surfaces, so that the shank portions 6a, 6b of the slide piece are pressed fast against 20 the guide bar 3. The cam and guide surfaces are so adapted that compression of the slide on the guide bar takes place upon an immaterial turning movement of the lever 10. At the continued 25 turning movement of the lever, the slide piece is thus clamped fast, the jaw 4 being then displaced by means of the cam surface 11 so as to bear rigidly against the work piece.

The taper of the pivot 8 is preferably chosen so as to be equal to or greater than the angle of friction of the material. When the work piece is to be loosened, it is only necessary to turn back the lever which is caused to be displaced upwardly by itself on the conical pivot owing to the resiliency of the shank portions of the slide piece. If desired, the taper angle may instead be made smaller, but then the risk is incurred that the lever is caused to stick so as not to permit of being carried upwardly by itself when turned into its inoperative position.

The rigid cam or guide surface is preferably adjustable in the vertical direction to permit of subsequent adjustments with respect to any wear occurring in the conical surfaces of the pivot and the lever. When a nut 14 is being made use of, such adjustments are undertaken by a turning movement of the nut, which on having been turned is secured in its new position by the locking pin inserted into the slot 15.

In the embodiment of the lever and the slide piece shown in Figs. 5 and 6, said slide piece presents, in the non-strained, that is to say non-compressed position of the pivot portions 8a and 8b, a greater width in the direction of resiliency of said parts than in the direction at right angles thereto. Here, the slit 9a is preferably of such

a width that the cross section of the pivot is substantially circular when the pivot portions are brought together. The opening 13a of the lever 10a is of an oval shape, as will appear from Fig. 5, and this shape substantially coincides with the shape of the pivot, when the pivot portions take the non-strained position shown in Fig. 6. In an arbitrary cross section through the opening of the lever, the smallest distance between the opposite sides is equal to or somewhat greater than the distance between the opposite sides in a corresponding cross section through the pivot, when the pivot portions are brought together. By turning the lever from its inoperative position in which the lateral surfaces of the opening of the lever consequently do not exert any pressure against the pivot portions, the latter may be moved toward each other, it being thus possible to press the shank portions of the slide piece 20 against the guide bar. Preferably, however, this action is attained only after the downward displacement of the lever is completed or at least approximately completed, an initial clamping effect of the slide piece having thus been obtained. On the continued turning of the lever, the pivot portions are brought together still further, the slide piece being then clamped so fast about the slide as to eliminate every risk of the displacement of the slide piece, when the jaw 4 is operated upon the cam surface 11. When this arrangement is used in combination with the conical pivot and the conical lever opening, the resistance to the downward displacement and thus to the turning of the lever can be made less than if the clamping of the shank portions of the slide piece were to be effected solely by downward displacement of the lever.

What I claim is:

1. A vise comprising a fixed jaw, a guide bar secured to said fixed jaw, a movable jaw, a member having a restricted possibility of movement relative to said movable jaw and being slidable on said guide bar, said slideable member having two resilient arms embracing said guide bar, said arms having at their ends pivot portions which together constitute a split pivot, and a lever mounted on said pivot and having cam means engageable with said movable jaw in a certain position of said lever to force said movable jaw towards said fixed jaw, said lever being mounted on said pivot for displacement around and along the axis of said pivot, means on said lever and said slideable member effective upon turning movement of the lever to produce displacement thereof along said pivot axis, and means on said lever and pivot effective upon such axial displacement of said lever in one direction to force said pivot portions towards each other so as to clamp said arms on said guide bar.

2. A vise as described in claim 1, said last named means comprising complementary conical surfaces on said lever and pivot portions.

3. A vise comprising a fixed jaw, a guide bar secured to said fixed jaw, a movable jaw, a member having a restricted possibility of movement relative to said movable jaw and being slidable on said guide bar, said slideable member having two resilient arms embracing said guide bar, said arms having at their ends pivot portions which together constitute a split pivot, and a lever mounted on said pivot and having cam means engageable with said movable jaw in a certain position of said lever to force said movable jaw towards said fixed jaw, said lever being pivotally mounted on said pivot and having a guide surface

engageable with a complementary surface on said slideable member upon turning movement of the lever to displace the lever along the axis of said pivot, and means on said lever and pivot to force said pivot portions towards each other and to clamp said arms on said guide bar upon said displacement of said lever along the pivot axis.

4. A vise comprising a fixed jaw, a guide bar secured to said fixed jaw, a movable jaw, a member having a restricted possibility of movement relative to said movable jaw and being slidable on said guide bar, said slideable member having two resilient arms embracing said guide bar, said arms having at their ends pivot portions which together constitute a split pivot, a lever mounted on said pivot and having cam means engageable with said movable jaw in a certain position of said lever to force said movable jaw towards said fixed jaw, and a guide surface on said slideable member, said lever being pivotally mounted on said pivot and having a guide surface engageable with said guide surface on said slideable member upon turning movement of the lever to displace the lever along the axis of said pivot, and means on said lever and pivot to force said pivot portions towards each other and to clamp said arms on said guide bar upon said displacement of said lever along the pivot axis.

5. A vise comprising a fixed jaw, a guide bar secured to said fixed jaw, a movable jaw, a member having a restricted possibility of movement relative to said movable jaw and being slidable on said guide bar, said slideable member having two resilient arms embracing said guide bar, said arms having at their ends pivot portions which together constitute a split pivot, a lever mounted on said pivot and having cam means engageable with said movable jaw in a certain position of said lever to force said movable jaw towards said fixed jaw, and a guide surface on said slideable member, said lever being pivotally mounted on said pivot and having a guide surface engageable with said guide surface on said slideable member upon turning movement of the lever to displace the lever along the axis of said pivot, and means on said lever and pivot to force said pivot portions towards each other and to clamp said arms on said guide bar upon said displacement of said lever along the pivot axis, and said guide surfaces having a small extension in the peripheral direction of said pivot, whereby to effect additional clamping action of said arms upon a further turning movement of said lever.

6. A vise comprising a fixed jaw, a guide bar secured to said fixed jaw, a movable jaw, a member having a restricted possibility of movement relative to said movable jaw and being slidable on said guide bar, said slideable member having two resilient arms embracing said guide bar, said arms having at their ends pivot portions which together constitute a split pivot, a lever mounted on said pivot and having cam means engageable with said movable jaw in a certain position of said lever to force said movable jaw towards said fixed jaw, and a guide surface on said slideable member, said lever being pivotally mounted on said pivot and having a guide surface engageable with said guide surface on said slideable member upon turning movement of the lever to displace the lever along the axis of said pivot, means on said lever and pivot to force said pivot portions towards each other and to clamp said arms on said guide bar upon said displacement of said lever along the pivot axis, and said guide surface

on said slidable member being adjustable in the axial direction of said pivot.

7. A vise comprising a fixed jaw, a guide bar secured to said fixed jaw, a movable jaw, a member having a restricted possibility of movement relative to said movable jaw and being slidable on said guide bar, said slidable member having two resilient arms embracing said guide bar, said arms having at their ends pivot portions which together constitute a split pivot, and a lever having an apertured portion mounted on said pivot and having cam means engageable with said movable jaw in a certain position of said lever to force said movable jaw towards said fixed jaw, said lever being mounted on said pivot for displacement around and along the axis of said pivot, means on said lever and slidable member effective upon turning movement of the lever to produce displacement thereof along said pivot axis, means on said lever and pivot effective upon such axial displacement of said lever in one direction to force said pivot portions towards each other so as to clamp said arms on said guide bar, said pivot having in the released position of said pivot portions a greater width in the

direction of resiliency of said portions than in a direction at right angles thereto, and the aperture of the lever engaging said pivot having corresponding dimensions so that the smallest distance between opposite sides of the aperture is equal to the width of the pivot in the compressed position of said pivot portions.
